Primary Examiner — Angela J Lee(74) *Attorney, Agent, or Firm* — Boudwin Intellectual Property; Daniel Boudwin(57) **CLAIM**

The ornamental design for an emergency vehicle light assembly, as shown and described.

DESCRIPTION

FIG. 1 shows a perspective view of the emergency vehicle light assembly.

FIG. 2 shows a front elevation view of the emergency vehicle light assembly.

FIG. 3 shows a rear elevation view of the emergency vehicle light assembly.

FIG. 4 shows a right side elevation view of the emergency vehicle light assembly.

FIG. 5 shows a left side elevation view of the emergency vehicle light assembly.

FIG. 6 shows a top plan view of the emergency vehicle light assembly; and,

FIG. 7 shows a bottom plan view of the emergency vehicle light assembly.

The broken lines shown in the Figures form no part of the claimed design.

The shade lines in the Figures show contour and not surface ornamentation.

1 Claim, 7 Drawing Sheets(56)
